UNITED STATES PATENT OFFICE.

FREDERIC HELMICK, OF FAIRMONT, WEST VIRGINIA.

MINE CAR.

Application filed October 21, 1924. Serial No. 744,915.

This invention relates to certain new and useful improvements in mine cars and more particularly to steel mine cars, the object being to provide a construction of mine car in which the sides are formed of a series of sections so that they can be rebuilt at the mine, thereby overcoming the difficulties now existing in steel mine cars where the sides are formed of a plate bent to the proper form.

Another object of my invention is to provide a mine car in which the angles of the sides are formed of rolled sections so as to provide a heavier cross section in the angle parts whereby a stronger and more durable mine car will be formed than when the sides are formed of a single plate.

In mine cars now in use the cars are often wrecked, the sides being bent and deformed to such an extent that it is impossible to rebuild the cars at the coal mine and in fact, impractical to rebuild them at all and the object of my invention is to provide a mine car in which the sides are formed of sections so that in case a car is wrecked, the car can be rebuilt at the mine by the average blacksmith.

The preferred form of steel mine car now in use is either provided with an oblique offset or a vertical offset and these offsets are obtained by bending a single plate to the proper angle so as to form a complete side, while with my improved construction, I form the offset of a series of angles riveted or bolted together so that they can be taken apart and straightened so as to rebuild the mine car readily without any great expense.

Other and further objects and advantages of the invention will be hereinafter set forth and the novel features thereof defined by the appended claims.

In the drawings,

Figure 1 shows a side elevation of a mine car constructed in accordance with my invention;

Figure 2 is a bottom plan view;

Figure 3 is a front end elevation, partly broken away;

Figure 4 is a rear end elevation;

Figure 5 is a modified form showing a detail vertical section showing the manner of constructing the vertical offset of angle irons;

Figure 6 is a vertical section of a slightly modified form showing an oblique offset; and

Figure 7 is a vertical section formed of three angle irons used in connection with a steel bottom.

In carrying out my invention as shown in Figures 1 to 4, I construct the sides of vertical plates 1, angle irons 2, 3 and 4 bolted together and preferably through to the ribs or binders 4', said rib or binders extending from the upper edge of the vertical side plates 1 under the bottom of the car to the upper edge of the opposite vertical side plate, the side plates being reinforced by angle irons 5. The angle iron 4 is bolted to the wooden bottom 6 by bolts 7, which extend through the rib or binders 4' as clearly shown.

The bottom of the car in the preferred embodiment of the invention is formed of wood as clearly shown and is reinforced by cross sills 8 at its ends and axle bases 9 are bolted to the bottom as clearly shown in which are mounted axles provided with the usual wheels, the particular construction of axle forming no part of my invention.

Extending longitudinally through the center of the car is a draft bar 10, the car being provided with bumpers 10' at its ends as clearly shown. The front end of the car is closed by an end door 11 and the rear by an end door 12 and the front rib 13 is braced as shown at 14 and the other ribs are offset as shown at 15 to provide a rigid support for the angles.

In the form shown in Figure 5 the side plates 16 have connected to their lower edges Z bars 17, which are bolted to angles 18, said bolts extending through the ribs 19 and wooden bottom 20.

In the form shown in Figure 6 a mine car is provided with an oblique offset, the Z bar 17' being employed to provide an upwardly sloping portion instead of a horizontal portion so that a rigid connection to the side plates 16' and angle irons 18' can be formed, the binder or rib 19' being constructed substantially the same as shown in the other embodiments of my invention and the upper edges of all of the side plates are reinforced by angle irons as clearly shown.

In the modification shown in Figure 7 a construction is shown substantially the same as shown in Figures 1 to 4 with the exception that a steel bottom 20 is used and comprises side plates 1', angles 2', 3' and 4".

In building up the sides of the car these angle irons are assembled and either bolted

or riveted to the ribs or binders and when a car becomes damaged in use, the bolts can either be removed or the rivets cut so that the angles constituting the sides of the car 5 can be removed and straightened and replaced.

While I have shown certain details of construction of a mine car, it is, of course, understood that I do not wish to limit myself to these details as my invention consists in constructing a steel mine car in which the angles of the sides are formed of rolled sections so as to increase the strength and to provide a mine car with sides formed 15 of a plurality of sections which can be easily assembled to build a car and which can be easily removed to repair the same.

From the foregoing description it will be seen that I have provided a metal mine car 20 with offset sides so constructed that the car body can be formed with a wooden bottom or a metal bottom, the offset sides being formed of upper vertically disposed plates and a series of angles formed of rolled sections connected together and to the ribs of the car to allow the sections to be readily detached in order to repair the body of the car when it becomes damaged in use.

It will also be seen that I have provided 25 a car body with open ends closed by end gates and constructed with ribs or binders to which the plates and angles are connected by rivets or bolts so that the sections can be readily assembled or detached when it becomes necessary to repair the car. In the 30 description I have not described the details of construction of the entire body of the car as my invention consists in the forming of the sides of the body of sections which can 35 be reshaped in order to allow the body of the car to be rebuilt at the mine, thereby overcoming the difficulties now existing in forming the sides of the car of a single plate bent to form offset sides.

40 What I claim is:

1. A body for mine cars comprising vertically disposed side plates, and a series of overlapping angle plates connecting said side plates to the bottom of the car to form 45 a car body with offset sides.

2. A mine car comprising a bottom, a rolled angled section, or plate, connected to said bottom, a second rolled angled section or plate, connected to the first mentioned

angled section or plate, a third rolled angled section or plate connected to the second mentioned rolled angled section or plate, upper part of sides connected to the last mentioned rolled angled section or plate and ribs extending around said plate and under the bottom of said car and to which said rolled angled section or plates are connected. 55

3. A mine car comprising a body having offset sides, the offset sides being formed of upper vertically disposed metal plates and a series of rolled angled sections or plates connecting said vertically disposed plates to the bottom of the car, ribs extending around said rolled angled sections or plates and means for connecting said plates to said ribs. 60

4. A metal mine car having offset sides, each side being formed of a series of rolled angled sections connected together and vertically disposed side plates connected to the upper angled section, said side plates having angles secured to the upper edges thereof. 75

5. A mine car having its sides formed of metal plates composed of vertically disposed upper plates and rolled angled sections or plates, connecting said vertically disposed plates to the bottom of the car, said plates being detachably connected to ribs extending around the outside of the car. 80

6. A mine car comprising a bottom, a rolled angled section connected to said bottom, having one of its legs extending vertically upwardly therefrom, a rolled angled section or plate connected to the vertical portion of the first mentioned angled section having its horizontal leg extending outwardly therefrom, a rolled angled section or plate connected to the last mentioned section or plate having a vertical leg and a side plate connected to the vertical leg of the last mentioned angled section or plate, said plates being detachably connected to ribs extending around outside of the body of the car. 90

7. A metal mine car having offset sides formed of a series of rolled angled sections or plates and vertically disposed plates, ribs extending around the outside of said plates, and under the bottom of the car and bolts or rivets connecting said rolled angled sections and plates to said ribs. 100

In testimony whereof I hereunto affix my 105 signature.

FREDERIC HELMICK.
